Primary Examiner — Justin M Jonaitis*Assistant Examiner* — Maheen Khurshid(74) Attorney, Agent, or Firm — JEEN IP LAW, LLC(57) CLAIM

The ornamental design for a beauty mask, as shown and described.

DESCRIPTION

FIG. 1 is a front, left and bottom perspective view of a beauty mask, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion of FIG. 5 thereof; and,

FIG. 10 is an enlarged view of a portion of FIG. 5 thereof. The dash-dash broken lines in the drawings represent portions of the beauty mask that form no part of the claimed design, The dot-dash broken lines in the drawings denote the boundaries of the enlarged detail views and form no part of the claimed design.

1 Claim, 10 Drawing Sheets(56)
